HIGH FIDELITY CABINET

Alfred R. Gilbert, Paoli, Pa., assignor to Philco Corporation, Philadelphia, Pa., a corporation of Delaware

Original application May 1, 1963, Ser. No. 74,694, now Design Patent No. 201,305, dated June 8, 1965. Divided and this application Mar. 3, 1965, Ser. No. 84,642

Term of patent 7 years

(Cl. D56—4)

FIG. 1.

FIG. 2.

FIG. 3.

FIG. 4.

FIGURE 1 is a front perspective view of a high fidelity cabinet, illustrating a compartment cover in open position, and showing an embodiment of my new design, wherein the fronts of the compartments have scroll work framing the top and bottom, the central open area is bounded along the top by a depending scroll work skirt comprising a plurality of curvilinear sections, and the legs and posts have curvilinear ornamental shape;

FIGURE 2 is an elevational view of the left side of the high fidelity cabinet shown in FIGURE 1, with said compartment cover shown in closed position;

FIGURE 3 is a front perspective view similar to FIGURE 1, showing another embodiment of my design, wherein the fronts of the compartments are bounded by substantially unadorned framing, the central open area is bounded along the top by a depending skirt having a single curvilinear section, and the legs and posts have frusto-conical ornamental shape; and

FIGURE 4 is an elevational view of the left side of the high fidelity cabinet shown in FIGURE 3, with both compartment covers shown in closed position.

As to each embodiment, the appearance of the side not shown is generally similar to the appearance of the illustrated side, and the back of each cabinet is substantially plain.

This is a division of design application Serial No. 74,694 filed May 1, 1963, now Patent No. D.201,305. I claim:

The ornamental design for a high fidelity cabinet, substantially as shown and described.
